Primary Examiner — Dominic V Simone(74) *Attorney, Agent, or Firm* — Lerner, David, Littenberg, Krumholz & Mentlik, LLP(57) **CLAIM**

The ornamental design for shoe upper element, as shown and described.

DESCRIPTION

FIG. 1 is a rear perspective view of a shoe upper element, according to my design;

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a bottom view thereof.

The broken lines shown in the drawings represent portions of the shoe upper element and exemplary footwear that form no part of the claimed design. The dash-dot lines indicate boundaries and form no part of the claimed design.

1 Claim, 6 Drawing Sheets(56)
